Seth Boynton

Letter Patent Issued June 7, 1874.

The Seth Boynton referred to on their Letter Patent and making part of the same containing a description in the words of the said Seth Boynton himself of his machine for splitting Hides & shaving Leather.

The wooden frame of this machine consists of two parallel pieces of timber framed together at the middle supported by four legs. From this frame rises the two series of the cutting machinery, made of iron or other metal & connected together by one or more metallic bars extending from side to side on the top. Within these sides in front are two iron or other sufficiently hard metallic cylinders with their pivot and casting on the sides placed perpendicularly one each. On the end of the uppermost of these rollers or cylinders is a square yoke or a shank projecting beyond the side for the purpose of receiving the work by which the roller is turned. This uppermost roller is arranged in a straight line horizontally or longitudinal on its surface. This roller may be placed at any required distance from the lower one by raising the frame in which it is mounted by means of some pins on the opposite end of these rollers to that on which the work is placed are two wheels the teeth of which not on each other, so that when the upper roller is turned communicates motion to the lower roller. Behind these metal cylinders or rollers there is an horizontal frame for the purpose of holding the knife in the proper position for cutting the leather or skin. This frame is made of metal & of such thickness or thickness as not to vibrate. It slides horizontally between the upright sides being guided by large iron plates above mentioned, so that the edge of the knife within it can be brought to the leather to cut or remove a back from it for the purpose of sharpening. This frame is suspended within the sides in its proper place by screws the heads of which are above the sides. This frame has two horizontal plates, extending from side to side so far apart as to admit of the knife being horizontally between them & of any required thickness. The knife being introduced & its edge advanced as far beyond the front of the frame as is thought necessary is then secured in its place by screws passing through the upper & lower plates of the frame & fastening with them.

and against the upper & lower surfaces of the knife plate. There are four rows of these screws extending from side to side near the edges of the upper & lower side plates. There are two thin or other metallic quoins which extend from the upper & lower plates forward towards the edge of the knife and are curved almost parallel to the corresponding ^{upper} lower metallic cylinders so that as the skin passes between the cylinders it cuts by the knife one portion rises on the frame & the other part descends below the lower cylinder & is attached by pins to a wooden roller underneath which draws it round it as fast as the operation of cutting is performed. This wooden roller is larger than and than the other & is turned by a square axis passing thro' a corresponding perforation in its centre, the ends or heads of this axis are rounded & rest upon the wooden frame. On one end of this axis is a notch at which a pin & a crank. The axis of the upper metallic cylinder are borne up or supported by means of springs attached to the outside of the side plates so that when the screws alone are loose there is room to set or place the edge of the knife. These springs hang when the upper cylinder is depressed by the screws. There is a strap or weight on the opposite end of the wooden roller to obstructs for the purpose of gradually turning the roller & winding the lower half of the skin upon it as the operation of splitting is performed. The whole of this machine may be made of cast iron except the knife. the screws pins cranks the iron axis which prefers this. the wooden roller & the springs. The method of using this machine is as follows. The knife being placed in the frame behind the rollers it is brought so far forward that the leather will touch its edge before it leaves the rollers between which it passes. Then grange the knife by the same pins in the frame to a proper distance from the roller so as to cut the under or grain side of the skin as desired. Confin the frame in its place by the screws in the side pieces & bring down the upper roller by the adjusting screws over its pivot to the thickness of the leather. After the machine is thus set in order the leather is laid on the table resting on the wooden frame in front of the rollers a man turns the crank on the axis of the upper roller whilst a boy drives the hand part of the skin between the rollers. The skin is thus drawn forward between the rollers, forced against the edge of the knife, confined and granged

gouges on the opposite side of the rollers which cuts it before it has escaped from their action & whilst this confined and shaves or splits it. The two gouges which come from the upper & lower plates of the frame meet the parts of the skin one upward & the other downward to the wooden roller (frame) which the sheep with the weight has been wound previously by the workmen to which it is fastened by striking it upon the pin in the roller by a wooden mallet. The part being raised from the metal roller wheel on the edge of this roller the weight & strap begin to act and draw forward the lower part of the skin as the cutting is performed cutting it upon the rollers. as the weight of the upper metallic roller is turned by the men, a boy at the same time is ready to raise or lower the end of the roller by means of the screws, as the thickness of the leather varies. In large hides the skin of the legs which is thin and never seems to splitting passes through in the small parts at each end of the rollers on a folded and wrinkled manner. When the knife wants re-sharpening the screws which confine the frame are raised & the frame drawn out on the table which rests on the wooden frame of machine. It is then slid in again & adjusted to its proper place. When the knife is to be ground the two upper rows of screw pins are slackened and the knife taken out for that purpose. As sides of leather are sometimes longer on the belly edge than on the back & as the grain side must go down next to the smooth roller & head first, when all the right hand sides are shaved the inner edge is drawn out of the wooden roller & the ends of the rollers are changed, when the skins of the leg go thru between the small parts of the rollers. The metal roller being perfectly cylindrical in that part opposite the knife & the wooden roller of greater diameter at one end than the other the skin will not conform equally to both. When the boy who stands at the table to face the rollers observes that one edge of the wooden roller stands higher than the other he will ease the screw on the opposite end which holds down the upper roller. This will slack the motion of the leather, tho' that end of the roller whilst the other end passes & it draws equally. When sheep & calf skins are to be shaved this wooden roller must be taken out and one put in that is a little smaller in the middle than at the ends. The force applied to this machine may be that of man, wind, water, horses as convenience shall dictate. Some

over this machine as highly useful to Tanners & Curriers for splitting
Hides from the lime and tan. That is to have them in one place where the
Curriers usually scrape off to make the leather of a proper thickness for the
purpose to which it is to be applied. Such ready hides are designed
for the upper leather of shoes & boots & for chairs & other carriages & the
whereas thin leather which may be obtained upon from the lime so that
it may be tanned sooner with less bark & more thoroughly. Calf-skin
shoes intended for ^{travelling} & other purposes that require very thin leather
may be shaved after tanning. When the hides are shaved in this manner
the price cut off is of considerable value whereas that scraped off in the usual
way is of no use. A man in a boy of eight or ten years of age will shave
8 or 10 in this manner to one in the usual way whilst the value of the first cut
off will be worth from 45 to 45 of the surface skin.

With Best Regards
